CABIN

Einar Svensson, 2248 NW. 190th Place,
Seattle, Wash. 98177

Filed Oct. 3, 1966, Ser. No. 4,123

Term of patent 14 years

(Cl. D13—1)

Fig. 1

Fig. 2

Fig. 3

FIGURE 4 is a side-elevational view of the cabin as viewed from the hidden side of FIGURE 1, and which cabin is presented on the slope of the hill.

I claim:

The ornamental design of a cabin, substantially as shown.
